[57] CLAIM

The ornamental design for a horticultural sprayer, as shown and described.

DESCRIPTION

FIG. 1 is a front perspective view of a horticultural sprayer showing my new design, on an enlarged scale;
FIG. 2 is a top plan view thereof;
FIG. 3 is a left side elevational view thereof;
FIG. 4 is a right side elevational view thereof;
FIG. 5 is a front elevational view thereof, the rear view being a mirror image;
FIG. 6 is a bottom plan view thereof.

FIG. 1

*FIG. 2**FIG. 3**FIG. 4**FIG. 5**FIG. 6*
